UNITED STATES PATENT OFFICE.

MAURICE ROSENFELD, OF NEW YORK, N. Y., ASSIGNOR OF ONE-HALF TO
HENRY W. SOLFLEISCH, OF HOMESTEAD, NEW JERSEY.

PRINTING-MACHINE.

SPECIFICATION forming part of Letters Patent No. 728,982, dated May 26, 1903.

Application filed May 22, 1902. Serial No. 108,460. (No model.)

To all whom it may concern:

Be it known that I, MAURICE ROSENFELD, a citizen of the United States, and a resident of New York city, borough of the Bronx, State 5 of New York, have invented certain new and useful Improvements in Printing-Machines, of which the following is a specification.

My invention relates more particularly to the class of printing-machines used for printing from engraved plates and the like; and it has for its object to provide means for guiding and feeding a continuous web or strip to be printed upon over said plate.

The invention consists in the novel details 15 of improvement that will be more fully hereinafter set forth and then pointed out in the claims.

Reference is to be had to the accompanying drawings, forming part hereof, wherein—

20 Figure 1 is a side elevation of a printing-machine provided with my improvements. Fig. 2 is an enlarged detail side elevation of part of the machine looking from the left in Fig. 4, part of the main frame being removed 25 and parts being in section substantially on the irregular line 2 2 in Fig. 4. Fig. 3 is a detail perspective view of the web-feeding devices; and Fig. 4 is an end elevation of the machine, partly in section, on the line 4 4 in 30 Fig. 2.

Similar numerals of reference indicate corresponding parts in the several views.

The machine I have illustrated, to which my improvements are applied, is generally 35 of the well-known construction commonly called a "D-roller plate-press," the numeral 1 indicating the main frame, 2 the reciprocative bed or platen for carrying the printing plate or type, 3 the D-roller carried in the 40 standards 1^a, and 4 the handle for operating said roller. The frame 1 has means, such as arms 1^b, for supporting one or more reels or rolls of webs or strips 5 to be printed. The web or strip 5 passes between the D-roller 3 45 and the printing-plate upon the bed 2 and is received by a take-up reel or spool 6. The latter is carried by a shaft 7, suitably supported, as by the standards 1^a.

The means I have shown for feeding the 50 web 5 intermittently or step by step and for taking up the slack and fed portions thereof

are arranged as follows: Upon the bed 2 are devices for gripping and releasing the web or strip 5, of which 8 indicates a bar carried by a frame or support 9, over which bar the web 5 passes, and a presser or gripper 10 is adapted to bear upon the web 5. (See Fig. 2.) The frame or support 9 is secured to bed or platen 2, as by a screw or bolt 11, and to permit adjustment the frame 9 has a slot 60 9^a to receive said screw or bolt. The presser or gripper 10 is swiveled to oscillate in the frame 9 and is shown carried by a bar or shaft 12, pivotally carried by frame 9, and said bar or shaft is provided with a head or 65 knob 13 for rotating it. To the frame 1, as by a bar 14, carried by the standards 1^a, is connected a shoe or plate 15, under which the head 13 is adapted to pass and to engage the same, whereby the bar or shaft 12 will be 70 turned on its axis to move presser 10. The head 13 may be provided with a friction or other suitable peripheral surface to coact with shoe 15 to cause the desired action of gripper 10. The shoe 15 is shown supported by guides 75 16, movably carried by a bar 17, extending from bar 14, so that the shoe may have vertical movement, and springs 18, interposed between the shoe 15 and bar 17, tend to depress said shoe. The forward end 15^a of shoe 15 is 80 inclined or beveled to permit the ready passage of head 13 under said shoe. When the bed 2 moves to the left in Fig. 1, the head 13 passes under and engages shoe 15 and causes said head to be rotated to the right in said 85 figure, thereby causing the presser 10 to clamp the web 5 upon bar 8, and when the bed 2 next moves to the right in Fig. 2 the head 13 is turned in the reverse direction, thereby releasing the presser 10 from the web 5. 90

To resist shocks and jars, I provide a member 19, hinged or pivoted on the bar or shaft 12 and having a spring 19^a interposed between the parts 19 and 10, and opposed to the member 19 is a spring-buffer 20, shown in the 95 form of a rod or bolt 21, carried by bar 14 and having a spring 22, as in Fig. 2. The part 19 may engage the buffer when bed 2 about reaches the limit of its stroke, and the springs will cushion shocks or jars. 100

When the D-roller 3 is rotated in the direction of the arrow in Fig. 2 and causes the

strip 5 to engage the printing plate or type on bed 2, the strip will be drawn the required amount from reel 6, which will rotate for the purpose, and to rewind the web 5, take up 5 the slack, and hold the web under tension I provide a spring-controlled take-up device, as follows: A convolute spring 25, having one end connected with the main frame and its other end arranged to operate with shaft 7, 10 thus normally tends to turn shaft 7 in the direction of the arrow *a* in Fig. 2 to wind up web 5 on reel 6. The spring 25 is to intermittently draw the web 5 and is connected with a drum 26 free to rotate with respect to 15 shaft 7, to which drum the inner end of said spring is connected, and said drum has a spring-actuated pawl 27, that engages a ratchet-wheel 28, secured to shaft 7. The drum 26 is rotated in the reverse direction 20 to arrow *a* to wind up the spring 25, as by a chain or connection 29, wound on said drum and connected with a treadle or the like 30. The spring can thus be wound at each operation of printing or when required.

25 As a convenient means for permitting the reel or spool 6 to be connected with and disconnected from shaft 7, I have shown the latter as jointed at 7^a and provided with a sleeve 7^b, Fig. 4, a spring 7^c serving to press said shaft to the left in Fig. 4. To adjust the 30 reels or spools 6 in position, the sleeve 7^b is moved from over the joint 7^a and the shaft 7 moved to one side of its normal position; but other means may be provided for this 35 purpose. A plurality of reels 5^a of the webs or strips 5 and a like number of receiving-reels 6 may be provided, and one or more of the web-feeding devices, so that several webs or strips may be printed simultaneously, and 40 suitable tension devices may be applied to the reels 5^a.

The operation of my improvements may be 45 described as follows: When the parts are in the position of rest and ready for the printing operation, the pressure-roller 3 will have its cut-away or flat part presented over the bed 2, the latter will be in the extreme position at the left, as in Fig. 1, the presser 10 will be in substantially the position as shown 50 in Fig. 1, with the head 13 under the shoe 15, and the web 5 will be drawn taut and so held between drum 26 and reel 5^a by spring 25. When roller 3 is now rotated in the direction of the arrow *b* in Fig. 2, its curved 55 surface will slip along web 5, and the bed 2 will be moved by the cam 3^a to the right in Fig. 2, at which time the head 13 will rotate backwardly under shoe 15 to open gripper 10 and release web 5, the gripper thereupon 60 sliding free of web 5 for the full length of such movement of bed 2. When the bed brings the printing-plate in the position to be pressed by roller 3 for printing upon the web 5, the latter will be gripped between the 65 roller and said plate, and the continued rotation of said roller will cause the web to be

drawn from reel 6, which latter will rotate backwardly. During such action the slack produced in the web between roller 3 and reel 5^a will be pushed toward the latter in 70 the intermediate space without any particular effect. When the roller 3 has been rotated so far that it is relieved from the printing-plate, the web 5 will be released and the spring 25 will cause the reel 6 to rewind the 75 web 5 until it is again drawn taut. Thereupon as roller 5 is next rotated in the direction reverse to the arrow *b* the roller will slip against the web until the roller again reaches its first-named inactive position, and simultaneously therewith the bed 2 will move to the left in Fig. 2, the gripper 10 sliding freely along the web, which still remains stationary; but as soon as the head 13 engages shoe 15 the presser 10 will be turned to clamp web 5 85 against bar 8, and the continued movement of the bed 2 to the left in Fig. 2 will cause the web 5 to be fed a corresponding amount until the bed comes to rest at the end of its stroke, (substantially as in Fig. 1,) the head 90 13 sliding under shoe 15 while the gripper 10 clamps the web, and the amount of web thus fed is taken up by reel 6. When the roller 3 is next rotated in the direction of arrow *b*, the bed 2 travels to the right in Fig. 2, as before 95 explained, and the amount of the web that has been fed (as just stated) will be drawn back from the reel 6 for the new printing section or surface of the web, and so on, as the printing operation is continued. It will be understood 100 that the amount of the web that is fed is determined by the distance that the head 13 slides under shoe 15 after gripper 10 has been turned to grip the web 5 against bar 8 and that the first movement of the bed 2 to the right in 105 Fig. 2 causes gripper 10 to release the web 5, owing to the rotation of head 13 under shoe 15.

By adjusting the support 9 upon bed 2 more or less toward or from the roller 3 the 110 amount of web to be fed for each printing impression will be determined, because thereby the head 13 will be permitted to have more or less sliding movement under shoe 15, while the gripper 10 holds and feeds the web 5. 115

When the spring 25 runs down, it may again be wound by operating treadle 30, and this may be done as often as required, the arrangement of the treadle connection 29 with drum 26 which I have set forth being a 120 convenient means for keeping spring 25 under more or less tension during operation, and this spring may be rewound for each one or several printing operations.

From the foregoing it will be understood 125 that each time that the roller 3 is oscillated back and forth new parts of the web 5 will be fed into printing position, and this intermittent feeding of the web is provided because in the plate-printing press illustrated 130 the bed or platen 2 is reciprocated under the D-roller 3.

Having now described my invention, what I claim is—

1. A printing-machine of the character described comprising a frame, a reciprocative bed or platen to carry a printing medium, a pressing or printing roller, means carried by said bed for intermittently feeding a continuous web or strip between said roller and said printing medium, means for adjusting the feeding devices along the bed for regulating the amount of web to be fed, and means for taking up the slack or fed portion of said web, substantially as described.

2. A printing-machine of the character described comprising a frame, a reciprocative bed or platen to carry a printing medium, a pressing or printing roller, means to supply a continuous web or strip to be printed between said medium and said roller, means for feeding the web or strip, a reel to receive the web or strip from said roller, and means to turn said reel in one direction to take up the fed portions of the web, said means being arranged to permit the reel to be turned in the opposite direction to enable the web to be drawn back from the reel during the printing operation, substantially as described.

3. A printing-machine of the character described comprising a frame, a reciprocative bed or platen to carry a printing medium, a pressing or printing roller, means to supply a continuous web or strip to be printed between said medium and said roller, means for feeding the web or strip, a reel to receive said web or strip, a spring to operate said reel to take up said web, and means to permit said reel to be turned backwardly against the tension of the spring, substantially as described.

4. A printing-machine of the character described comprising a frame, a reciprocative bed or platen to carry a printing medium, a pressing or printing roller, means to supply a continuous web or strip to be printed between said medium and said roller, means for feeding the web or strip, a reel to receive the web or strip, a spring, a ratchet and pawl interposed between said reel and spring, and means for winding up the spring after it has operated the reel through the medium of the ratchet and pawl, substantially as described.

5. A printing-machine of the character described comprising a frame, a reciprocative bed or platen to carry a printing medium, a pressing or printing roller, gripping devices connected with said bed or platen, means for supporting a web between its ends so as to be engaged by said gripping device to intermittently feed the web, and reels for supporting the web, one of the reels being arranged to

oscillate to permit fed portions of the web to be drawn back, substantially as described.

6. A printing-machine of the character described comprising a frame, a reciprocative bed or platen to carry a printing medium, a printing or pressing roller, a gripping device connected with said bed or platen and comprising a bar and a movable presser to coact to grip a web, means for operating said presser to grip and release said web, and reels for supporting the web, one of the reels being arranged to oscillate to permit fed portions of the web to be drawn back, substantially as described.

7. A printing-machine of the character described comprising a frame, a reciprocative bed or platen to carry a printing medium, a pressing or printing roller, a gripping device connected with said bed or platen and comprising a bar and a movable presser to coact to grip a web, said presser having a rotary head, and a shoe to be engaged by said head, the head and the shoe being arranged to cause the presser to grip the web when the head first engages the shoe, the head thereafter sliding in contact with the shoe during the continued stroke of the bed, substantially as described.

8. A printing-machine of the character described comprising a frame, a reciprocative bed or platen to carry a printing medium, a pressing or printing roller, a frame or support carried by said bed and having a bar to receive a web, a presser to operate with the web and movably carried by said frame or support, said presser having a rotary head, and a spring-operated shoe to be engaged by said head, the head and the shoe being arranged to cause the presser to grip the web when the head first engages the shoe, the head thereafter sliding in contact with the shoe during the continued stroke of the bed, substantially as described.

9. A printing-machine of the character described comprising a frame, a reciprocative bed or platen to carry a printing medium, a pressing or printing roller, a support carried by said bed and having a bar to receive a web, a presser to operate with the web, means to operate said presser, a member movably connected with said presser, a spring to coact therewith, and a buffer connected with the main frame to coact with said member, substantially as described.
